UNITED STATES PATENT OFFICE

ERNEST O. FREDERICS, OF NEW YORK, N. Y., ASSIGNOR TO E. FREDERICS, INC., OF NEW YORK, N. Y., A CORPORATION OF NEW YORK

HAIR CURLING DEVICE

Original application filed October 12, 1928, Serial No. 311,994. Divided and this application filed June 7, 1930. Serial No. 459,641.

This invention relates to hair-curling devices, and particularly to devices for winding tresses of hair for hair-waving treatments; the present application being a division of my co-pending application Serial No. 331,994, filed October 12, 1928.

In general, it is an object of the invention to provide a device of the character described which is simple and economical of manufacture and on which tresses of hair may be readily and securely wound.

Another object is to provide improved means for facilitating the winding of hair on a curling device.

Other objects of the invention will in part be obvious and will in part appear hereinafter.

The invention accordingly comprises an article of manufacture possessing the features, properties and the relation of elements which will be exemplified in the article hereinafter described, and the scope of the application of which will be indicated in the claims.

For a fuller understanding of the nature and objects of the invention reference should be had to the following detailed description taken in connection with the accompanying drawings, in which:

Fig. 1 is a partly sectional view of one form of hair-curling device constructed in accordance with the invention; and

Fig. 2 shows the curling device with the hair wound thereon.

In winding tresses of hair on a curling device, and particularly in the "Croquignole" method of winding, in which laterally spread tresses of hair are wound upon themselves on a curling device, it is desirable to provide means for permitting a free rotation of the curling device, in the direction in which the hair is to be wound, while resisting rotation in the opposite direction.

There is shown in my co-pending application, above referred to, one form of such device wherein the curler is provided at one end with a knob and at the other end with a key member or supporting means to which there is attached means fitting within one end of the curler for controlling the rotation there-

of. The present invention contemplates the provision of a curler of the type under consideration, wherein the supporting means is rigidly held in place by an independent element whereby lateral movement of the curling element with respect to the holding element is prevented and whereby strain on a rotation-controlling mechanism is eliminated.

One form of device embodying the invention is shown in the drawings. This device comprises a curling element 10 having at one of its ends a knob 11 by which it may be rotated, and at the opposite end a holding or attaching element 12, which is adapted to be held permanently in place when the device is in use. The holding element 12 has formed thereon a sleeve 13 which fits into a recess 14 in the other end of the curling element, and which fits about a coil spring 17 extending within a reduced diameter of recess 18, which is disposed inwardly of the recess 14. In order to prevent a lateral movement of the holding element 12 and the sleeve 13 with respect to the curling element 10, there is fixedly mounted on the holding element 12 a rod 19 which, in the present instance, extends entirely throughout the length of the curler and carries at its free end a disk 20, which fits within a recess 21 in the knob. There is thus provided a sturdy and easily-operable construction wherein transverse movements of the sleeve 13, which will tend to result in inefficient operation as well as in unnecessary wear, is avoided.

Since certain changes may be made in the above article and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I

claim as new and desire to secure by Letters Patent, is:

1. A hair-curling device, comprising a curling element, an attaching element, a stepped chamber at the end of the curling element adjacent said attaching element, a sleeve on said attaching element extending into the outer portion of said chamber, a spring fitting within said sleeve and within the inner portion of said chamber, a knob at the other end of said curling element and formed with a recess therein, a rod connected with said holding element and extending through said curling element, and a securing disk attached to the end of said rod and fitting within the recess of said knob.
2. A hair-curling device, comprising a curling element, an attaching element, a stepped chamber at the end of the curling element adjacent said attaching element, a sleeve on said attaching element extending into the outer portion of said chamber, a spring fitting within said sleeve and within the inner portion of said chamber, and a member carried by said holding element and extending into said curling element for preventing longitudinal movement of said curling element with respect to said holding element.
3. A hair-curling device comprising a curling element, a holding element, means to prevent relative rotation of said curling element and said holding element in one direction while permitting relative rotation of said elements in the other direction, and a member carried by said holding element and extending into said curling element for preventing longitudinal movement of said curling element with respect to said holding element.
4. A hair-curling device comprising a curling element, a holding element, means to prevent the relative rotation of said elements in one direction while permitting relative rotation thereof in the other direction, and a rod connected with said holding element and extending through said curling element and provided with a disk-like member at its further end for preventing relative longitudinal movement of said holding element and said curling element.

In testimony whereof I affix my signature.
ERNEST O. FREDERICKS.
